UNITED STATES PATENT OFFICE.

ROBERT B. EWART, OF DETROIT, MICHIGAN.

ROTARY VALVE.

1,131,776.

Specification of Letters Patent. Patented Mar. 16, 1915.

Application filed January 30, 1913. Serial No. 745,226.

To all whom it may concern:

Be it known that I, ROBERT B. EWART, a citizen of the United States of America, residing at Detroit, in the county of Wayne 5 and State of Michigan, have invented certain new and useful Improvements in Rotary Valves, of which the following is a specification, reference being had therein to the accompanying drawings.

10. This invention relates to improvements in internal combustion engines and more particularly to a valve construction and arrangement therefor, the object of the invention being to provide a simple and efficient seat for the valve which will prevent leakage, and further, to provide an arrangement whereby pressure upon the valve caused by the explosions within the cylinder is reduced to a minimum without unduly 20 restricting the passage leading from the cylinder to the valve.

25. A further object of the invention is to provide a novel construction of spring packing members and to provide certain other new and useful features in the construction and arrangement of parts, all as hereinafter more fully described.

30. To these ends the invention consists in the matters hereinafter set forth and more particularly pointed out in the claims reference being had to the accompanying drawings in which—

35. Figure 1 is a transverse vertical section through the upper end or head of the cylinder of an engine embodying the invention; Fig. 2 is a longitudinal vertical section of the same showing a pair of cylinders and a seat block and valve in side elevation; Fig. 3 is a horizontal section through the cap and 40 valve substantially on the line III—III of Fig. 1; Fig. 4 is a section similar to Fig. 1 showing a modified construction; and Fig. 5 is a plan view of Fig. 4 with the cap removed.

45. For convenience of illustration, the invention is shown as applied to a four-cylinder engine of the vertical type in which the cylinders are cast *en bloc*, but it will be understood that the invention may be applied 50 to other types of engines having any desired number of cylinders cast in any suitable manner.

55. In the drawing, 1 indicates the engine cylinder having water jackets 2 and an upwardly extending head portion 3 which is faced off to form a seat for a cap member 4,

said head and cap being also formed with a water space communicating with the water jacket of the cylinders. The cap is secured firmly to its seat on the head by means of bolts 5 passing through openings in the cap and engaging screwthreaded openings in the head. The head 3 is formed with a channel or chamber which is rectangular in cross section, this channel extending across the upper ends of the several cylinders when said cylinders are cast *en bloc*, or said channel may extend across one or more of the cylinders as desired. Fitting within this channel or chamber is a seat block 6 which 60 may be formed in a single piece to extend from end to end of the channel across the several cylinders or it may be divided transversely between the cylinders into two or more parts. In its upper side this block is 65 formed with a semi-circular seat for a cylindrical valve 7 and the cap 4 is formed with a like semi-cylindrical seat for the valve. The block is also formed in its lower side with ports and passages 8 adapted to register with intake and exhaust ports 9 and 10 respectively in the valve. A reduced neck portion 11 connects the upper end of each cylinder with the channel portion 12 of the head and each connecting portion is bored 70 out to receive a tubular extension 13 on the seat block, said tubular extensions being attached to the block by screwthreading their upper ends to engage screwthreaded openings in the blocks or they may be formed integral with the block as desired. Each extension 13 forms a passage opening into the upper end of the cylinder at its lower end and connects with the passage in the block leading from the port 8 therein which is 75 elongated in the direction of the length of the block and contracted laterally to give the desired width of bore which has a capacity equal to the capacity of the bore of the tubular extension 13. Each of these extensions 13 is provided with a plurality of 80 packing rings 14 so that compression will be held in the cylinder against escape upward around the seat block.

85. The seat block is of slightly lesser vertical width than the depth of the channel in the head and to hold it yieldingly in contact with the lower half of the valve, it is formed along its two side edges with a series of spring members 15 resting upon the bottom 90 of the channel and yieldingly supporting the block. These spring members are each 100

formed integral with the edge of the block by cutting a groove 16 in the bottom of the block at a short distance from each edge thus leaving a depending portion at each 5 edge of the block which is partially severed therefrom by slits 17 formed by sawing into the sides of the block at a distance from its lower edge equal to the depth of the groove 16 and then cutting the depending portion 10 vertically at 18 intermediate the ends of each slit 17 to form spring portions extending laterally from a portion which connects them with the body of the block between the ends of the slits 17. The lower edge of 15 each spring member 15 is cut away slightly so that it will bear upon the bottom of the channel in the head at its ends only, and the bottom of the block is cut away in a like manner so that the whole block will be supported 20 entirely by the yielding ends of the spring members. The block is preferably formed of cast iron or other suitable metal and as these spring members are an integral part thereof they will not be readily affected 25 by the high temperature caused by the continued explosions taking place in the upper end of the adjacent cylinder. The block may, if desired, be cored out longitudinally at 19 for the purpose of lightness and giving 30 a better cooling effect.

The cylindrical valve 7 may be of any suitable construction but is preferably of the form shown. This valve in itself and independently of the construction and arrangement of the other parts forms no part 35 of this invention as it has been made the subject of a separate application filed by me and now pending in the United States Patent Office. The form of this valve however, 40 makes it particularly adaptable for use with this particular construction and arrangement of seat block as said valve operates in conjunction with a single passage leading therefrom into the upper end of the cylinder. The valve comprises a cylindrical shell or wall 20 and end walls 21, one of which end walls is formed with an outwardly extending axial trunnion or shaft 22 by means 45 of which the valve may be turned in timed relation to the movement of the engine pistons 23 in any suitable manner. The shell of the valve is provided with a series of openings 24 arranged around the valve opposite each inlet passage 25 formed in a cap 50 and a like series of openings 26 is provided in the wall of the valve opposite each exhaust passage 27 in the cap. To register with each of the ports 8 leading into the upper ends of the cylinders when the valve is 55 turned, are two inlet ports 9 arranged diametrically opposite each other, and in like manner two exhaust ports 10 are arranged in the wall of the valve at diametrically opposite points to also register with each of 60 said ports 8. The ports of each pair of ports 65

9 are connected by a passage 28 formed by transverse walls 29 extending across the valve and these walls also form passages 30 at each side thereof into which the inlet ports 10 open. At one end of the ports 9, 70 the two walls 29 are connected by a wall 31 which closes one side of the passage 28 and at the opposite end of said ports the walls 29 are connected to the wall of the shell of the valve by walls 32 which close one side 75 of the passages 10. The passages 28 and 30 thus open laterally, longitudinally of the valve in opposite directions to connect with those portions of the valve into which the exhaust and inlet passages open respectively. 80 In this construction of valve, adjacent cylinders have a common intake and others a common exhaust, and a single passage for each cylinder serves to admit the charges thereto and conduct the exhaust therefrom, 85 giving a very compact construction and permitting the passage to be made of ample size in the tubular extension 13 to give a free entrance and exit of the gases without having an extended area exposed to the 90 force of the explosions and thus causing a heavy pressure on the valve.

In Figs. 4 and 5 of the drawings, a circular recess or chamber is formed opposite the upper end of each cylinder to receive a 95 cylindrically shaped seat block 33, said blocks being each formed with a semi-cylindrical seat across its upper end for the valve and also with an integral tubular extension 34 similar to the extension 13 formed with 100 a passage leading to the adjacent port 8 in the valve seat. These blocks are also each formed with a series of spring members along its lower peripheral edge formed in a manner similar to that of the members 15, 105 and each block is of greater diameter than the diameter of the valve so that it will extend upwardly at each side of said valve to the horizontal plane of the longitudinal axis thereof and form an extended seat for the 110 valve. By providing the tubular extension in which the passage 8 is formed, a much smaller area is exposed to the force of the explosions than would be exposed if the lower end of the block itself extended 115 through or formed the upper end wall of the cylinder.

Obviously other changes may be made in the construction and arrangement of parts without departing from the spirit of my invention and I do not limit myself to the particular form or construction shown.

Having thus fully described my invention what I claim is:

1. In an engine, the combination of a plurality of cylinders each having a bore extending through the end thereof, a cylindrical valve having ports opening through the sides thereof, a cap for all of the cylinders rigidly secured thereto and formed with a 125

- seat for half of the valve and with inlet and exhaust passages adapted to register with the ports in the valve, a block extending across and seated upon all of the cylinders 5 beneath the cap and formed with a seat for the other half of the valve and provided with extensions each engaging a bore in the end of a cylinder, said block and extensions being formed with passages opening into the 10 cylinders and adapted to register with the ports in the valve, and means for yieldingly holding said block in contact with said valve.
2. In an engine the combination with a cylinder and a cylinder portion having a passage opening into said cylinder, and formed with a valve seat, of a valve engaging the valve seat to control said passage, a member preventing leakage between said 15 valve and its seat, yielding means for holding said member in operative position comprising a plurality of spring members formed by partially severing the portions of said member therefrom.
3. In an engine, the combination with a cylinder, a cylinder portion formed with a valve seat, and a passage leading therefrom to the cylinder, a rotatable valve controlling said passage, of a member adapted to engage 20 said valve and prevent leakage around the same, and a plurality of spring fingers formed integral with said member to hold the member in yielding contact with the valve.
4. In an engine, the combination with a cylinder, a cylinder portion having a passage communicating with the interior of the cylinder, and a cylindrical valve controlling said passage, of a seat member forming a 25 seat for the valve, and means for holding said member in yielding contact with the valve comprising a plurality of spring fingers formed integral with said member by partially severing edge portions of the 30 member therefrom.
5. In an engine the combination with a cylinder having a passage leading thereto and a rotatable cylindrical valve controlling the said passage, of a member engaging the 35 valve, and means for holding said member in yielding contact with the valve comprising a plurality of spring fingers formed by slotting the metal at a distance from the edge thereof parallel with said edge at intervals and cutting through said edge at 40 right angles to said slots intermediate the ends thereof to form spring members ex- 45 tending laterally from the portion which is integral with the body of the member between the adjacent ends of the slots. 60
6. In an engine the combination with a cylinder, a cylinder portion formed with a chamber and a cap secured to the cylinder portion and formed with one-half of a valve seat, of a seat block in said chamber formed 65 with the other half of a valve seat, a cylindrical valve engaging said seats, and means for yieldingly holding the block in contact with the valve comprising a series of spring fingers formed by providing a channel in 70 the bottom of the block at a distance from its edge, and slots in the sides cutting through at intervals into said channel, the severed depending portion thus formed being cut at right angles to the slots to form 75 integral spring fingers extending laterally from the portions between the adjacent ends of the slots, and said spring fingers being cut away between their ends to form supporting projections at the extreme ends of 80 said fingers.
7. In an engine, the combination with a plurality of cylinders, of a head portion formed with a chamber extending across the ends of the cylinders and having neck portions connected with the upper ends of the cylinders and formed with bores connecting the interior of the cylinders with the chamber, a seat block in said chamber formed 85 with a valve seat which is semi-circular in cross section and provided with a port opposite each cylinder, tubular extensions on the block engaging the ports and opening into the upper ends of the cylinders to form 90 passages leading from the ports in the seat block, packing rings on said extensions, a cap secured to the head and formed with a valve seat which is semi-circular in cross section and with passages leading from said seat, a rotatable cylindrical valve engaging 95 the seat in the block and the seat in the cap and provided with passages having ports adapted to register with the ports in the block, and a series of spring fingers formed integral with the block along its lower edges 100 to engage the bottom of the chamber and yieldingly hold the block in contact with the valve. 105

In testimony whereof I affix my signature in presence of two witnesses.
